[57] **CLAIM**

The ornamental design for a fishing pole holder or the like, substantially as shown and described.

DESCRIPTION

FIG. 1 is a perspective view of the fishing pole holder, or the like, showing my new design and having a portion of a lower rod portion thereof broken away; FIG. 2 is a top plan view thereof; FIG. 3 is a rear-elevational view thereof; FIG. 4 is a side-elevational view thereof, the opposite side being the same as the side shown; FIG. 5 is a front-elevational view thereof; and FIG. 6 is a bottom view thereof.
